M. J. WAPLE

DISCHARGING DEVICE FOR VENDING MACHINES

Filed Jan. 5, 1923

UNITED STATES PATENT OFFICE.

MARSHALL J. WAPLE, OF WASHINGTON, DISTRICT OF COLUMBIA.

DISCHARGING DEVICE FOR VENDING MACHINES.

Application filed January 5, 1923. Serial No. 610,821.

To all whom it may concern:

Be it known that I, MARSHALL J. WAPLE, a citizen of the United States, residing at Washington, District of Columbia, have invented certain new and useful Improvements in Discharging Devices for Vending Machines, of which the following is a specification, reference being had therein to the accompanying drawings.

10 This invention relates to a discharging device for vending machines, and the object of the invention is the construction of a simple and efficient discharging device, whereby when the coin controlled device is 15 properly operated an article, such as a pencil, can be easily and accurately vended.

With this and other objects in view, my invention comprises certain novel combinations, constructions and arrangements of 20 parts as will be hereinafter described, illustrated in the accompanying drawings, and more particularly pointed out in the appended claims.

25 In the drawings:

Figure 1 is a view, in side elevation, of a vending machine constructed in accordance with the present invention, while

Figure 2 is a transverse, sectional view of the machine.

30 Figure 3 is a sectional view of the machine, taken on line 3—3, Fig. 2, looking in the direction of the arrows.

Figure 4 is a fragmentary, perspective view of the hopper bottom of the machine.

35 Figure 5 is a perspective view of one of the agitating devices.

Referring to the drawings by numerals, 1 designates the casing, and 2 is the cap-like end. In the casing 1 is positioned discs 40 3 and 4. A rib 5 is fastened to the inner face of casing 1 and is normally seated in the notches 6 (Fig. 2) of the discs 3 and 4 for locking the discs against rotary movement within the casing.

45 The hopper bottom 7 comprises the primary section 8 and the auxiliary section 9. The primary section 8 is provided with a short angular lower edge 10, whereas the auxiliary section is provided with a comparatively long angular edge 10^a. These sections 8 and 9 are provided with registering slots 11 through which the agitating devices 12 work. These agitating devices are provided in their bodies 13 with, preferably, 55 square apertures 14 through which the operating shaft 15 extends. Shaft 15 is pro-

vided at one end with a grip 16, whereby the operator turns the shaft and causes the agitating devices 12 to work through slots 11. The coin controlled device 17 (Fig. 3) is 60 fully described in my co-pending application entitled, "Coin controlled device for vending machines," filed Jan. 5, 1923, Serial No. 610,820.

Each agitating device includes said body 65 13 and an outwardly curved guide finger 18. In the body is formed pocket 19 for receiving the article, such as a pencil (see Fig. 2), and upon the operator turning shaft 15 a single pencil will be discharged into 70 the holder 20, as shown by dotted lines, Fig. 2. When the agitating devices are in position for discharging a single pencil, or like article, a pencil will be seated in notch 21, and from actual experience with a working 75 machine I know that no jamming will be permitted. The rounding of the upper edge 22 of body 13 also keeps the pencils from jamming but the devices 12 agitate the pencils, or articles, in the hopper sufficiently 80 to cause them to be properly placed for discharging one at a time as a proper coin is deposited through slot 23, Fig. 3. It should be noted that when the agitating devices are turned to a discharging position the pencil 85 will roll along the upper edges of the fingers 18 and can not become disengaged from the fingers until they reach their lowermost position indicated by dotted lines in Figure 2 and can not pass out of the casing until 90 the fingers have partially returned to the original elevated position.

While I have described the preferred embodiment of my invention, and have illustrated the same in the accompanying drawings, certain minor changes or alterations 95 may appear to one skilled in the art to which this invention relates, during the extensive manufacture of the same and I, therefore, reserve the right to make such alterations 100 or changes as shall fairly fall within the scope of the appended claims.

What I claim is:

1. In a dispensing machine, the combination of a casing provided with an outlet a 105 hopper in the casing having an outlet above the outlet of the casing, a plurality of oscillating article agitating and discharging devices mounted in the casing and movable through the hopper and outlet thereof, each 110 of said devices being provided with an article receiving pocket and with a finger ex-

tending from the pocket, for engaging an article to be dispensed and preventing discharge of the article through the outlet of the casing until the discharging device has 5 been swung in one direction its full extent and then partially returned to its original position.

2. In a dispensing machine, the combination of a casing provided with an outlet a 10 hopper in the casing having an outlet above the outlet of the casing, a plurality of oscillating agitating and discharging devices mounted in the casing and movable through the hopper and outlet thereof, each of said 15 devices being provided with an article receiving pocket and with a finger extending from the pocket for engaging an article to be dispensed and preventing discharge of the article from the casing through the outlet 20 of the casing until the discharging device has been swung in one direction its full extent and then partially returned to its original position, the upper portion of said agitating and discharging device being provided 25 with an article holding notch and an article agitating cam edge.

3. A vending machine comprising a casing having an outlet, a hopper in said casing and having an outlet above the casing outlet 30 a rocker shaft rotatably mounted beneath the hopper, and article discharging means carried by said shaft and having oscillating movement across the outlet of the hopper into and out of a discharging position when 35 the shaft is rotated, said means comprising a vertically disposed plate having its lower portion engaged with said shaft and its upper portion extending into said hopper, said plate having an inner side portion provided 40 near its lower end with an article receiving recess and beneath said recess pro-

vided with an elongated upwardly curved article engaging finger for engaging an article to be dispensed and preventing discharge of the article through the outlet of the casing until the plate has been swung downwardly its full extent and then partially returned to its original position, the upper edge of said plate being bowed upwardly for the greater portion of the width 50 of the plate and merging into an article receiving recess at the junction of the upper edge and inner side edge of the plate.

4. A vending machine comprising a casing having an outlet, a hopper in said casing and having an outlet above the casing outlet, a rocker shaft mounted beneath said hopper, and article discharging means carried by said shaft and extending upwardly therefrom for movement through the lower 60 portion of the hopper and across the outlet thereof into and out of a discharging position when the shaft is rotated, said means comprising a plate connected with said shaft, and an elongated finger extending 65 from the inner side of said plate for extending across the outlet of said hopper and for engaging an article to be dispensed and preventing discharge of the article from the casing until the plate has been swung downwardly its full extent and then partially returned to its original position, the upper edge of said plate being provided with an upwardly bowed cam forming portion for agitating articles in the hopper when the 70 plate is moved by turning of the shaft and said cam edge merging into an article receiving recess at the junction of the upper edge with the inner side edge of the plate.

In testimony whereof I hereunto affix my 75 signature.

MARSHALL J. WAPLE.
